[57] CLAIM

The ornamental design for the tiedown hook, as shown and described.

DESCRIPTION

FIG. 1 is a front elevational view of one embodiment of a tiedown hook according to my new design, a rear elevational view is a mirror image of FIG. 1;
FIG. 2 is a right side elevational view thereof;
FIG. 3 is a left side elevational view thereof;
FIG. 4 is a bottom plan view thereof, a top plan view is a mirror image of FIG. 4;
FIG. 5 is a front elevational view of another embodiment of the tiedown hook, a rear elevational view is a mirror image of FIG. 5;
FIG. 6 is a right side elevational view thereof;
FIG. 7 is a left side elevational view thereof; and,
FIG. 8 is a bottom plan view thereof, a top plan view is a mirror image of FIG. 8.
